United States Patent Office.

WALKER B. BARTRAM, OF DANBURY, CONNECTICUT.

Design No. 2,584, dated February 19, 1867.

DESIGN FOR THE FRAME OF A SEWING MACHINE.

The Schedule referred to in these Letters Patent and making part of the same.

TO ALL WHOM IT MAY CONCERN:

Be it known that I, WALKER B. BARTRAM, of Danbury, in the county of Fairfield, and State of Connecticut, have invented a new and useful Design for the Casting of a Sewing Machine; and I do hereby declare the following to be a full, clear, and exact description of the same, reference being had to the accompanying drawings, in which—

The figure represents a side elevation of my machine.

The frame A presents the form and appearance of a tapered bar or rod, curved in a circle, and forming about two-thirds of a complete circle. The larger end of this bar A is joined to a convex disk, B, which forms the base upon which the frame or bar A and the sewing mechanism are supported. The upper or smaller end of the bar B supports the guide-head C, in which the presser-bar D and needle-bar F have their bearings. A little above the base B, and located upon the frame A, is the cylindrical case F, within which the spool G of sewing-thread is placed. The needle-arm H corresponds in form with the frame A, and is pivoted thereto directly behind the spool-case F, so that this joint and the connection of the needle-arm to the driving-pulley I, is entirely concealed. From the front edge of the disk B, and joined to the larger end of the bar or frame A, projects upward and forward, in a graceful curve, the stout arm J, upon the extended end of which is the head K, upon which the sewing-table L is secured. The driving-shaft M has its bearings in the head K and in the frame A, behind the spool-case F. The form of the needle-arm corresponds with the form of the frame A, and the two present an unbroken curve from the guide-head C to the spool-case F, imparting an air of grace and lightness. The head K and sewing-table on the one side are balanced by the spool-case and driving-pulley on the other; and altogether there is presented an appearance of artistic proportion arrangement highly satisfactory; while the large open space, enclosed by the frame and needle-arm, is very useful.

I claim the design for the casting of a sewing machine, as shown and described.

W. B. BARTRAM.
